UNITED STATES PATENT OFFICE.

GEORGE BOWER AND ANTHONY S. BOWER, OF ST. NEOTS, COUNTY OF HUNTINGDON, ENGLAND.

FURNACE FOR EFFECTING THE PROTECTION OF IRON AND STEEL SURFACES.

SPECIFICATION forming part of Letters Patent No. 270,005, dated January 2, 1883.

Application filed December 3, 1880. (Model.) Patented in England September 20, 1880, No. 3,811; in France October 2, 1880, No. 138,960; in Belgium October 4, 1880, No. 52,711; in Germany October 10, 1880, No. 14,196; in Austria December 1, 1880, No. 5,180; in Sweden February 3, 1881, No. 26; in Norway May 14, 1881, and in Canada October 12, 1881, No. 13,531.

To all whom it may concern:

Be it known that we, GEORGE BOWER and ANTHONY SPENCER BOWER, subjects of the Queen of Great Britain, and residing respectively at St. Neots, county of Huntingdon, England, have invented certain Improvements in Effecting the Protection of Iron and Steel Surfaces and in the Furnaces Employed Therein, (for which we have obtained a patent in Great Britain No. 3,811, dated 20th September, 1880,) of which the following is a specification.

This invention relates chiefly to an arrangement of furnace best adapted to perform the operations of oxidizing and deoxidizing the surfaces of iron and steel according to the processes known as Bower's processes, for which a patent has been obtained, dated November 16, 1880, No. 234,524. The said processes consist in the formation of a protective film or coating of oxide or oxides of iron upon the iron and steel surfaces by the action of carbonic anhydride (CO_2) at a suitable temperature or by taking articles having a slight coating of sesquioxide of iron or rust, or producing upon the articles to be protected a coating of sesquioxide of iron or rust by submitting such articles to the action of carbonic oxide mixed with a larger quantity of air than is requisite for conversion into carbonic anhydride, and then in either case reducing the sesquioxide to the magnetic or black oxide by submitting the articles to the action of carbonic oxide alone, the operations being in all cases performed with the aid of an elevated temperature. According to the present invention these processes are carried out in a furnace, which embodies the following features, videlicet: The furnace is so constructed that the carbonic oxide from the generator being caused to meet with a current of hot air, combustion takes place, which is perfected before the products therefrom are admitted to the chamber containing the articles to be coated and the waste products of combustion are caused to pass on their way to the chimney over and among a series of pipes through which the cold air required for combustion is admitted so as to become heated and prepared for admixture with

the carbonic oxide, as before mentioned. Continuous regeneration therefore takes place, and the operations are effectively performed under the most economical conditions.

In order that the said invention may be perfectly understood, we shall now proceed more particularly to describe the improved furnace, and for that purpose shall refer to the several figures on the accompanying sheet of drawings, the same letters of reference indicating corresponding parts in all the figures.

Figure 1 of the accompanying drawings represents a longitudinal section of the furnace, taken along the line 1 2 in Figs. 2, 4, 5, and 6. Figs. 2 and 3 are transverse vertical sections of the same, taken respectively along the lines 3 4 and 5 6, Fig. 4; and Figs. 4, 5, and 6 are horizontal sections taken respectively along the lines 7, 8, 9, 10, and 11 12, Figs. 1, 2, and 3.

a a a are the producers for gasifying the fuel employed which is supplied through hoppers *b b b*. The carbonic oxide from the combustion of the fuel in the producers *a a a* passes along a conduit, *d*, (its flow being controlled by a slide, *c*), to the openings *e*, where this combustible gas meets a current of hot air ascending through a passage, *f*, and is consumed. The products of combustion are thence conducted along a passage, *g*, where they are thoroughly mixed by open brick-work cross-walls, *h*, and then return along a passage, *i*, whence they enter through the oblong holes *l*, the chamber *k*, in which the articles to be coated are arranged. After having passed over and among the articles to be coated, the waste escapes downward through ports *m* into regenerator-chambers *p*, and thence to the chimney-flue *s*, heating in its passage the tubes *t*, composing the regenerator, and which are securely supported by the cross-walls *W*. Cold air enters the apparatus at *v* through a channel provided with a regulating valve under the control of the furnace-tender. This air then passes along the lower rows of regenerator-tubes and back through the upper tubes, thus becoming highly heated by the waste gases and capable of developing greater heat when burned with the combustible gas, as here-

inbefore described. The oxidizing and deoxi-
dizing processes take place according as the
air or gas is in excess, and this is readily con-
trolled by the gas-damper and air-regulator
5 hereinbefore described. When it is desired to
use liquid hydrocarbons for generating the
gas, troughs containing the liquid are simply
inserted in the producers *a*, so that the liquid
will be vaporized, and the gas or vapor given
10 off applied in the same manner as the carbonic
anhydride. When gaseous hydrocarbon—such
as coal-gas—is used, the producers *a* are
simply dispensed with, the gas having already
been made and being introduced into the flue *d*.
15 When common coal-gas or any other hydro-
carbon gas is used, a furnace constructed in the
manner hereinbefore described may also be
employed for conducting the operations of
producing the protective coating. In many
20 situations it will be convenient to place the
gas-producers some distance from the furnaces
proper. A close muffle or retort may also be
placed inside the oxidizing-chamber, and thus
be heated externally by the gases from the gas
25 producers or generators, while the articles to
be coated may be placed inside the muffle or
retort, and coal-gas or hydrocarbons may be
consumed with varying quantities of air within
the muffle.
30 In some cases common coal-gas or other hy-
drocarbon gas or pure hydrogen gas may be
used both for heating the chamber and for ox-
idizing, and such gas may be obtained from
any independent source. Rusty articles placed
35 within the oxidizing-chamber may have the

rust upon them reduced to a protective coat-
ing by passing the coal-gas or other hydro-
carbons or hydrogen gas among them without
any mixture of air whatever. This operation
can also be effectively performed in the oxi-
dizing-chamber by opening out the gas-damper
40 and only allowing sufficient air to pass through
the valve *v* to keep up the heat required in
the chamber. In this manner a strongly re-
ducing flame is obtained which is quite suffi-
cient to reduce the surfaces of very rusty ar-
ticles in a few hours to a rustless surface.
45

We claim as our invention—

1. The combination of gas-producing cham-
bers, flue *d*, air-inlet *f*, and passage *g*, having 50
open cross-walls *h*, with coating-chamber *k*,
communicating with said passage, regenera-
tor-chambers *p*, having air-tubes passing
through them and leading to the inlet *f*, all
substantially as set forth.

2. The combination of the chamber *k* and
passage *g*, having open cross-walls *h* with pas-
sage *i* and chambers *p*, the latter having air-
tubes, all substantially as described.

In testimony whereof we have signed our 65
names to this specification in the presence of
two subscribing witnesses.

GEORGE BOWER.

ANTHONY SPENCER BOWER.
